UNITED STATES PATENT OFFICE.

ALVIN CAROLL GODDARD, OF WOODCLIFF, NEW JERSEY.

WINDOW-SASH.

SPECIFICATION forming part of Letters Patent No. 763,747, dated June 28, 1904.

Application filed March 23, 1904. Serial No. 199,527. (No model.)

To all whom it may concern:

Be it known that I, ALVIN CAROLL GODDARD, a citizen of the United States, and a resident of Woodcliff, in the county of Hudson and State of New Jersey, have invented 5 a new and Improved Window-Sash, of which the following is a full, clear, and exact description.

This invention relates particularly to that 10 class of window-sash adapted to slide vertically in the window-casing and to swing on horizontal pivots, so that the sash may be turned to any desired angle or completely reversed for convenience in washing both sides 15 of the glass by a person within the room; and the object is to provide a simple mechanism permitting the movements with ease and without noise.

A further object is to provide a novel means 20 for attaching the sash-chains to the sashes.

Other objects of the invention will appear in the general description.

I will describe a window-sash embodying my invention and then point out the novel 25 features in the appended claims.

Reference is to be had to the accompanying drawings, forming a part of this specification, in which similar characters of reference indicate corresponding parts in all the figures.

30 Figure 1 is a side elevation, partly in section, of a window-sash and attachment embodying my invention. Fig. 2 is a sectional elevation thereof. Fig. 3 is a sectional detail showing the means for attaching a chain 35 to the sash. Fig. 4 is an elevation thereof. Fig. 5 is a section on the line $\alpha\alpha$ of Fig. 1. Fig. 6 is a similar section, but showing the sash as swung on its pivots. Fig. 7 is a sectional detail showing the means for locking 40 the guide-strips at certain times. Fig. 8 is a face view showing a modified means for attaching the chains, and Fig. 9 is a sectional view thereof.

45 Referring to the drawings, 1 designates the lower sash, and 2 the upper sash, both operating in the window-casing 3. As the connections between the casing and both sashes are alike, a description of one will answer for both. It may be here stated that practically 50 the usual form of sash is employed, it being

a trifle narrower, however, than the usual sash, and therefore no special mechanism is required for the construction.

Arranged at both sides of the casing with-in the channels formed between the stop-bead 55 4 and the stop-strips are guides 5, which, as here shown, consist of metal; but it is to be understood that they may be made of wood. Each guide-strip has a central vertical channel 6, and at the sides thereof are ribs 7 for 60 engaging in correspondingly-shaped channels 8, formed in the side rails of the sash. It will be noted that the opposite sides of the ribs 7 are inclined or cam-shaped, the object of which will hereinafter appear. The guide- 65 strips are held yieldingly against the sash by means of plate-springs 9, secured to the window-casing and engaging at their ends with the said strips. While I have shown three of these springs, one at the top, one at the bot- 70 tom, and one at about the center, it is obvious that more may be employed, if desired. The inward movement of the strips is limited or regulated by stop-screws 10, which engage in the casing and abut against the inner sides 75 of the strips. When the sash is raised, turned, or entirely removed, it may be necessary to lock the lower end of the guide-strips from outward movement. For this purpose I pro- 80 vide latch-hooks 11, having swinging connec- tion with the lower portion of the casing and extended through openings 12 in the guide- strips. By forcing the lower portion of the guide-strips inward the hook portion of the latch will engage with the outer side of the 85 lower wall of the openings 12, and when it is desired to release the same it is only necessary to raise the outer end of the latch.

Slidable in the channel 6 of each guide-strip is a device for attachment to the sash and also 90 for attachment to the weight-chain. This device consists of a boxing 13, open at its inner side and also having an opening at the top and an opening at the bottom. At the lower opening there are inwardly-extended flanges 95 14 for engaging with the sides of a lower link of the chain 15. These links, it will be noted, are substantially triangular in form, with the wider portions downward, so they will wedge in between the flanges 14. The chains are 100

further attached to the boxings by means of lugs 16 17, one near the bottom and the other near the top, these lugs passing through links of the chain. By this construction the chain 5 may be readily attached or detached. It will be understood, of course, that the chains pass over the usual pulleys at the top of the sash and connect with weights.

Extended outward from the boxing 13 is a 10 sash-attaching lug 18, designed to pass through a keyhole-shaped opening 19, formed in a plate 20, attached to the side rail of the sash. The lug 18 has a projection 21, adapted to pass through the reduced portion of the opening 19. By this arrangement the sash may be 15 readily removed by reversing the same, so as to bring the narrow portion of the opening 19 downward and in line with the downward projection 21 of the lug. By pressing the 20 guide-strip inward the lug will be moved out through the opening. Inward of the plate the side rail is provided with a recess 22, permitting a free swinging movement around the lug and its projections.

25 In the operation the sash may be readily slid up and down in the usual manner, the guide-strips being held in their outer positions against the sash. When it is desired to swing the sash on its pivotal lugs, it is only 30 necessary to draw the upper or lower end outward, and the inclined or cam-shaped edges of the ribs 7 by engaging with the corresponding side walls of the channels 8 will cause the guide-strips to be pressed inward against 35 the resistance of the springs 9. The parts will then be in a position substantially as indicated in Fig. 6.

In Figs. 8 and 9 the chain-attaching device 40 consists of a boxing 23, the side walls of the channel therein being provided with notches 24, conforming to the chain-links, and these notches extend in opposite directions from a center block 25, with which a screw-lug 26 45 engages and serves the same purpose as the lug 18.

Having thus described my invention, I claim as new and desire to secure by Letters Patent—

1. The combination with a window-sash and a window-frame, of guide-strips arranged in 50 the side channels of the frame, springs arranged in the channels for pressing the guide-strips outward, the said guide-strips having vertical channels and vertical ribs at the sides of the channel, the sash being provided with 55 channels to receive said ribs, chain-attaching devices movable in the channels of the guide-strips, and pivotal connections between said devices and the sash.

2. The combination with a window sash and

frame, of vertically-disposed spring-pressed 60 guide-strips at opposite sides of the frame, the said guide-strips having central vertical channels and ribs at the opposite sides of the channels the side walls of said ribs being inclined, the side rails of the sash being provided with 65 channels shaped to said ribs, chain-attaching devices movable in the channels of the guide-strips, and pivot-lugs carried by said devices and having removable engagement with the side rails of the sash. 70

3. The combination with a window sash and frame, of spring-pressed guide-strips at opposite sides of the frame, the said guide-strips having central vertical channels and ribs at the opposite sides of the channels, the sash 75 side rails having channels for receiving said ribs, boxes movable in the channels of the strips open at the inner side and also having openings at the top and bottom, flanges extended inward from the lower end of the boxes, 80 a chain having links adapted to wedge between said flanges, lugs in the boxes for engaging in other links of the chain, and pivot-lugs on the boxes having connection with the side rails of the sash. 85

4. The combination with a window sash and frame, of guide-strips arranged between the stop-bead and stop-strips of the frame, springs arranged between said stops and pressing against the inner sides of the guide-strips, 90 means for limiting the inward movement of the guide-strips, the said guide-strips having vertical channels and vertical ribs at the sides of the channels, the sash being provided in its side rails with channels to receive said ribs, 95 chain-attaching devices movable in the channels of the guide-strips, plates attached to the side rails of the sash and having keyhole-openings, and lugs attached to the chain-attaching devices and having downward projections 100 adapted to pass through said keyhole-openings.

5. The combination with a window sash and frame, of guide-strips arranged in the spaces between the stop-beads and stop-strips of the 105 frame, springs for pressing the guide-strips outward, chain-attaching devices movable in the guide-strips and on which the sash is mounted to swing, and locking devices for holding the guide-strips inward against the 110 pressure of the springs at the lower end.

In testimony whereof I have signed my name to this specification in the presence of two subscribing witnesses.

ALVIN CAROLL GODDARD.
